UNITED STATES PATENT OFFICE

2,020,988

WIND AND WATER PROOFING SHINGLED
HOUSE CORNERSJoseph Balletta, Jamaica Beach, N. Y., assignor of
one-half to Abraham Bashuk, Brooklyn, N. Y.

Application September 13, 1934, Serial No. 743,897

1 Claim. (Cl. 20—1)

This invention relates to a device for wind and waterproofing the corner of a shingled house or building.

When houses or buildings, either new or old, are shingled, especially with asphalt shingles, it is always difficult to secure a tight joint at the vertical corners of the building. As the result thereof, the shingles at the corner are often blown loose by the wind, and rain is allowed to penetrate beneath the corner, rotting the frame of the building, and damaging the inside of the house. The same problems which arise at the corners of the house likewise arise around the edges of window frames or wherever the line of shingles starts on the side of the house.

This invention overcomes this form of difficulty and makes it possible to provide a wind-proof and water-proof joint between the asphalt shingles and any corner or edging or framework on the house.

A further object of this invention is to provide a wind and waterproofing device for the corner of the house which, while intended for use with asphalt shingles, may also be used with any type of shingles. One form of the invention is particularly intended for corners of the house and another form is intended for use along a window frame or for use along any vertical edging on the house. This latter form may likewise be used on each side of every shingle, if desired, along the entire side of the house.

In the preferred form, this invention is performed out of copper, but it will be obvious that it may be made of any other type of sheet material, and especially of sheet metal. It is also included within the object of this invention that the device may be made of any suitable material, such as molded composition matter.

With the foregoing and other objects in view, as will hereinafter become apparent, this invention comprises the constructions, combinations and arrangements of parts hereinafter set forth, claimed and illustrated in the accompanying drawing:

Fig. 1 is a horizontal sectional view of the invention applied to a corner of a house, taken approximately on the line 1—1 of Fig. 2.

Fig. 2 is a side elevation of the same.

There is shown at 10 a schematic representation of the clapboards forming the corner 11 of a house or other building, wherein it is desired to apply shingles of asphalt, or other types of shingles, along the side thereof. Shingling the side of a house is a very desirable form of finishing the outside thereof, except for the objection

that the shingles are easily loosened by wind and rain along the corners thereof, or wherever a vertical edge of the shingle is exposed.

Instead of applying the asphalt shingles 12, 13, 14 and 15, directly to the clapboards or frame 10 on opposite sides of the corner 11, the device 16 of this invention is fitted along the outside of the corner 11. This device 16 is of a height equal to the height of the corner of the house that is being protected thereby and is of a width sufficient to allow the necessary folds shown on the drawing to be made therein so that the entire device will be preferably from a single sheet of copper. The device 16 consists of two U-shaped channel members 17 and 18, each channel member having long legs 19 and 20 which fit along the outside of the clapboards 10 at the corner 11 of the house. As will be observed, these channels 17 and 18 are placed at right angles to each other, whereby the long legs 19 and 20 are at right angles to each other, and thereby enclose the corner of the house.

Short legs 21 and 22 complete the channel members 17 and 18. These short legs 21 and 22 are integrally connected to each other by having portions 23 and 24 folded back from the ends of the legs 21 and 22 in parallelism thereto and then connected by an integrally curved strip 25. As will be observed, the channel members, 17 and 18 including their long and short legs, the parallel portions, and the curved strip 25, are all part of one integral piece of any material folded into this form, the sheet material being preferably sheet copper.

It will be understood that other sheet material, such as sheet aluminum or aluminum alloy, may be used, if desired, and furthermore that the device 16 need not necessarily be made of copper or metal but instead may be made of a molded composition matter or made of reinforced asphalt, if desired.

The space enclosed by the bases of the channels 17 and 18 and the curved strip 25 may be left hollow, or, if desired, a quarter molding of suitable size may be inserted therein to reinforce the same.

In applying this invention to the corner of a house, the device 16 is applied along the corner 11 and then nails 26, suitably spaced, are inserted through the long legs 19 and 20 of the channels 17 and 18. After this device 16 is thus put into position, the asphalt shingles 12, 13, 14 and 15 are placed with their edges in the channel portions and secured to the house in the usual manner, the shingles being placed either in parallelism with each other or in overlapped relation if desired.

Another form of this invention is made in the form of a channel 30 having a base 31, a long leg 32 and a short leg 33. This form 30 is intended for use along any vertically exposed edge of the shingles 12 and 13 which is not at the corner of the house. This vertical edge may be along the frame of a window or door, for instance, or, if desired, this form 30 may be used on the opposite vertical edges of every shingle. This form 30 is likewise secured to the clapboards 10 of the house by nails 26.

As will be apparent, with this invention, either in form 16 or form 30, secured in the appropriate place as above described in connection with the shingles on the side of the house, it is impossible for wind to get under the vertical edges of the shingles to tear them loose or for rain to penetrate them because no vertical edges are left exposed to the water.

20 This invention may be applied to a new house, when shingling the same, and may be likewise with equal facility, applied to old houses when the vertical sides are being refinished with shingles.

25 The novel features and the operation of this device will be apparent from the foregoing description. While the device has been shown and

the structure described in detail, it is obvious that this is not to be considered limited to the exact form disclosed and that any changes may be made therein within the scope of what is claimed without departing from the spirit of this invention.

5

Having thus set forth and disclosed the nature of this invention, what is claimed is:

A device for windproofing and waterproofing a vertical corner of a building, comprising a unitary piece of sheet copper, said sheet copper being formed into two channeled members and a joining strip, said channeled members being formed with a long leg and a short leg and a joining member between said long and short legs and at right angles thereto, each long leg being adapted to receive fastening means for securing the device in operative position, said joining strip connected to the ends of said short legs, said joining strip being curved to a quarter circle whereby said channel members are at right angles to each other so as to be secured on both sides of the building corner, the channels in said channel members being adapted to receive the vertical edges of the building shingles.
